ATTORNEYS

UNITED STATES PATENT OFFICE.

DILLON EDWARD MAPOTHER, OF LOUISVILLE, KENTUCKY.

CLIP.

SPECIFICATION forming part of Letters Patent No. 758,547, dated April 26, 1904.

Application filed May 13, 1902. Serial No. 107,116. (No model.)

To all whom it may concern:

Be it known that I, DILLON EDWARD MAPOTHER, a citizen of the United States, and a resident of Louisville, in the county of Jefferson and State of Kentucky, have invented a new and Improved Clip, of which the following is a full, clear, and exact description.

The object of the invention is to provide a new and improved clip or sealing device for envelopes, bags, and like articles which is simple and durable in construction, easily applied, and arranged to securely close the mouth of an envelop or bag to prevent the contents thereof from falling out and becoming lost while in transit and on removal of the device from the bag or envelop to allow postal or customs authorities or other persons to inspect the contents of the envelop or bag whenever it is necessary to do so, the device being also capable of fastening covers to deeds and of being used for other purposes.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a front elevation of the improvement as applied on an envelop, a portion of which is broken out. Fig. 2 is a rear elevation of the same. Fig. 3 is an enlarged cross-section of the same on the line 3 3 of Fig. 1. Fig. 4 is a front elevation of a modified form of the improvement as applied to an envelop, part of which is broken out. Fig. 5 is a like view of another modified form of the improvement as applied to an envelop, part of which is broken out. Fig. 6 is a transverse section of the same on the line 6 6 of Fig. 5, the envelop being omitted. Fig. 7 is a front elevation of another modified form of the improvement as applied to an envelop. Fig. 8 is a like view of another modified form of the improvement as applied to an envelop, part of which is broken out. Fig. 9 is a transverse section of the same on the line 9 9 of Fig. 8,

the envelop being omitted; and Fig. 10 is a front elevation of another modified form.

The improved clip or sealing device is preferably made of spring-wire; but other suitable spring material may be used; and the said clip or sealing device, as illustrated in Figs. 1, 2, and 3, consists, essentially, of registering and connected front and rear clamping members or jaws A and B, made approximately U shape, the middle or horizontal bar of the front clamping member A being divided and terminating in rearwardly-extending hooks C to engage the under side of the fold D' of the envelop or other article D clamped between the members A and B. The hooks, owing to their resiliency, can be readily sprung into position to engage the under side of the fold D' after the upper end of the envelop and its folded portion are forced between the clamping members A and B, as will be readily understood by reference to Figs. 1, 2, and 3. The hooks C thus form retaining means to hold the clip or sealing device against accidental disengagement with or displacement from the article, so that the clamping members effectively clamp the parts in position to prevent opening of the envelop or bag or to prevent loose sheets and covers engaged by the device from becoming disconnected.

The hooks C may have that portion resting upon the under side of the fold of varied shapes to enlarge the surface-engaging fold or may terminate in points or sharp edges E for piercing the material clamped between the members A and B to securely lock the hooks in position, and consequently the whole device, to prevent removal of the latter from the article unless the points or cutting edges are first disengaged from the material of the article.

The connecting parts F of the front and rear clamping members A and B form saddles, which rest on the top edge of the article, thus holding the clip or sealing device against undue downward movement on the article, the hooks C acting in a like manner to prevent upward movement of the clip or device.

The form of the clamping members, the retaining means, and the locking device may be

greatly varied, according to the intended use of the clip or sealing device, without deviating from my invention. For instance, the clip or sealing device shown in Fig. 4 is more especially designed for fastening papers to a cover, the arrangement permitting of adding sheets of paper to the ones already in place without detaching the clip. In this case the clamping members A' and B' when the clip is not in use lie in the same plane, and the rear clamping member B' is U-shaped and connected at its ends by the longitudinally and inwardly extending connecting-bars F', with the divided parts of the front clamping member A' terminating in outwardly-extending hooks C', adapted to engage the fold at the lower edge and back thereof, as will be readily understood by reference to Fig. 4.

To insert additional sheets of paper, it is only necessary to raise the members A' and insert the sheets under the fold, when upon the release of the members the sheets will be clamped and held in place.

In the modified form shown in Fig. 5 the front clamping member A² has its divided portions connected with each other by the hook C² for engaging the fold, as described above, and the rear member B² is made in two parts, each terminating in a pin E², adapted to engage or pierce the material at the back of the envelop D. (See Fig. 6.)

In the modified form shown in Fig. 7 the hook C³ connects the parts of the front clamping member A³ with each other, the front and rear clamping members having their ends spiral shaped.

As shown in Fig. 8, the rear clamping member B⁴ is U-shaped and connected by the connecting-bars F⁴ with the parts of the front clamping member A⁴, each terminating in a hook C⁴, which may have a forwardly-extending pin E⁴ to pierce the inside portion of the fold D' of the envelop D.

In the modified form shown in Fig. 10 the clip is made of an integral length of spring-wire formed intermediate of its ends into V-shaped clamps F² and G for engaging the exterior of the folded body, the ends of the spring-wire being bent abruptly to form hooks H for engaging the interior of the folded body. The hooks H are preferably formed into eyes at their ends, so as not to present sharp edges, and flattened or not, as may be preferred.

From the foregoing it is evident that the clip is very simple and durable in construction and can be readily applied to close the mouth of envelops, bags, and the like or to fasten covers to deeds and other papers, it being understood, however, that in each case the hook or hooks engage the inner edge of the folded part, so as to prevent accidental displacement or detachment of the clip from the parts engaged, and if used the points or sharp edges

pierce the material of the parts engaged to 65 securely lock the clip or sealing device in position.

I do not limit myself to the form of clip shown and described, as it is obvious that it can be readily made into various other shapes 70 without deviating from the spirit of my invention.

Having thus described my invention, I claim as new and desire to secure by Letters Patent—

1. A clip or sealing device for bags, envelopes, covers and other articles having a fold, comprising front and rear spring clamping members of approximately equal length, connected together and adapted to securely clamp the article inserted between the members, the connecting portions of the members forming saddles to rest upon the top edge of the article, and an upwardly-extending spring retaining means on one of the members, adapted to be sprung in place underneath the fold 80 and to clamp said fold against the part from which it is projected, as set forth.

2. A clip or sealing device for bags, envelopes, covers and other articles having a fold, comprising front and rear registering spring 90 clamping members connected together and adapted to securely clamp the article inserted between the members, the connecting portions of said members forming saddles to rest upon the top edge of the article, upwardly-opening 95 spring retaining means on one of the members, said means being adapted to be sprung in place underneath the fold, and an integral locking means on the clip, to pierce the material of the article inserted between the clamping members, as set forth.

3. A clip or sealing device for bags, envelopes, covers and other articles having a fold, comprising front and rear registering spring 105 clamping members connected together and adapted to securely clamp the article inserted between the members, the connecting portion of the members forming saddles to rest upon the upper edge of the article, and upwardly-opening 110 spring-hooks on one of the members, adapted to be sprung in place underneath the fold, as set forth.

4. A clip or sealing device for bags, envelopes, covers and other articles, comprising front and rear spring clamping members, of which the rear member is made U shape and the front clamping member is similarly shaped and divided, the ends of the divided parts of the front member terminating in upwardly-opening hooks for engaging the under side of 115 the fold, as set forth.

5. A clip or sealing device for bags, envelopes, covers and other articles, comprising front and rear spring clamping members, of which the rear member is made U shape and the front clamping member is similarly shaped and divided, the ends of the divided parts of the front member terminating in upwardly- 120 125

opening hooks, engaging the fold, and the said hooks having sharpened portions for piercing the material of the bag, as set forth.

6. A clip made of an integral length of 5 spring-wire, said wire being formed into **U**-shaped clamping members for engaging the exterior of a folded body, one of said members having its ends bent to form upwardly-opening hooks for engaging the interior of

10 said folded body and clamp the fold against the parts from which the hooks extend.

In testimony whereof I have signed my name to this specification in the presence of two subscribing witnesses.

DILLON EDWARD MAPOTHER.
